PACK CARRIER

Allen M. Battles, Randolph, Vt.

Application December 23, 1932, Serial No. 648,673

3 Claims. (Cl. 224—25)

The present invention relates to a pack carrier and has for its prime object to provide a convenient and inexpensive device for the purpose of carrying a load fastened to the back of the 5 person.

Another object of the invention resides in the provision of a device of this nature which is simple in its construction, inexpensive to manufacture, comfortable to wear, thoroughly efficient and 10 reliable in use and otherwise well adapted to the purpose for which it is designed.

With the above and numerous other objects in view as will appear as the description proceeds, the invention consists in certain novel features 15 of construction, and in the combination and arrangement of parts as will be hereinafter more fully described and claimed.

In the drawings:

Figure 1 is a side elevation of the pack carrier 20 showing the same in use.

Figure 2 is a rear elevation thereof.

Figure 3 is a perspective view of the frame.

Figure 4 is a perspective view of one of the sheet metal strips.

Figures 5, 6 and 7 are detail sections taken 25 respectively on the lines 5—5, 6—6 and 7—7 of Figure 2.

Referring to the drawings in detail it will be seen that the frame which is illustrated by itself 30 in Figure 3 comprises a pair of vertical spaced parallel coextensive side rods 5 connected together by cross rods 6 and 7. The rods 5 merge at their bottom ends in rearwardly directed extensions 8 which terminate in oblong transverse loops 9. The upper ends of the rods 5 merge into 35 forwardly and downwardly curved shoulder extensions 10. At the junctures of the extensions 10 with the rods 5 there are fixed oblong transversely disposed loops 11.

Oblong strips of sheet metal or the like each 40 comprise an elongated body 12 merging at its bottom end in a rearwardly directed ledge 14 and at its upper end in a forwardly and downwardly curved shoulder extension 15. The rods 45 5 are fixed centrally and longitudinally on the bodies 12 and the shoulder extensions 10 curve over the extensions 14 and portions of the extensions 8 adjacent the rods 5 rest on the ledges 14. Under the shoulder extensions 15 and adjacent 50 portions of the bodies 12 there are secured pad- 17. Straps 18 are secured to the loops 11 for engage- 55 ments with buckles 19 mounted on strap sections 20 secured in the loop 9. The pack, of course is

thus supported on the frame by the straps 18 as is illustrated to advantage in Figure 1.

The construction of the carrier is such that said carrier is not fastened to the body by extraneous means such as straps, etc., and it can therefore be 60 readily removed for resting and suspended by the shoulder extensions 10 from any suitable support out of engagement with the ground. It will further be seen that the person upon which the carrier is mounted is free to sit down, as on a 65 log or the like, in which position the bottom of the carrier may rest on the ground, thereby relieving the shoulders of the weight of the load. Still further, the carrier will not interfere with buttoning or unbuttoning the outer garments of 70 the person upon which it is mounted and said person will also have the free use of his arms and hands. It will also be noted that, due to the construction of the carrier the person is free to crawl on his hands and knees, and in fact, enjoy sub- 75 stantially complete freedom of the body. The simplicity of construction will, it is thought, add materially to the pleasure of hiking, as will be apparent.

It is thought that the construction, utility and 80 advantages of this invention will now be clearly understood by those skilled in this art without a more detailed description thereof.

The present embodiment of the invention has 85 been described in considerable detail merely for the purposes of exemplification since in actual practice it attains the features of advantage enumerated as desirable in the statement of the invention and the above description.

It will be apparent that changes in the details 90 of construction, and in the combination and arrangement of parts may be resorted to without departing from the spirit or scope of the invention as hereinafter claimed or sacrificing any of its 95 advantages.

Having thus described my invention, what I 100 claim as new is:

1. A pack carrier of the class described comprising a frame which includes a pair of spaced parallel coextensive rods, cross bars connecting the rods, the lower ends of the rods merging into rearwardly directed extensions which terminate in integral oblong transversely disposed loops, the upper ends of the rods merging into forwardly and downwardly curved shoulder extensions, oblong loops across the junctures of the shoulder extensions with the rods, oblong strips comprising elongated, flat, relatively wide bodies to the longitudinal centers of which are fixed said rods and said bodies extending from the lower to the 110

upper ends of said rods and merging at their upper ends into forwardly and downwardly curved shoulder extensions over which extend the shoulder extensions of the frame.

5 2. A pack carrier of the class described comprising a frame which includes a pair of spaced parallel coextensive rods, cross bars connecting the rods, the lower ends of the rods merging into rearwardly directed extensions which terminate in integral oblong transversely disposed loops, the upper ends of the rods merging into forwardly and downwardly curved shoulder extensions, oblong loops across the junctures of the shoulder extensions with the rods, oblong strips comprising elongated, flat, relatively wide bodies to the longitudinal centers of which are fixed said rods and said bodies merging at their upper ends into forwardly and downwardly curved shoulder extensions over which extend the shoulder extensions of the frame, and the lower edge of the bodies merging into rearwardly directed ledges underlying the extensions at the bottom ends of the rods, padding under the shoulder extensions of the strips and adjacent portions of the body straps secured to the second mentioned loops, strap sections secured to the first mentioned loops and having buckles, for detachable connection to the first-named straps.

3. A pack carrier of the class described com-
